(57) **CLAIM**

The ornamental design for an electronics enclosure, as shown and described.

DESCRIPTION

FIG. 1 is a top and front perspective view of an electronics enclosure showing my new design;

FIG. 2 is a top and front perspective view thereof, shown in environmental use;

FIG. 3 is a front elevational view of FIG. 1;

FIG. 4 is a front elevational view of FIG. 2; and,

FIG. 5 is a rear elevational view thereof.

The broken lines environment is for illustration only and forms no part of the claimed design.
